J. T. WILLIAMS.
ELECTRO MAGNETIC TRANSMITTER.

No. 433,381.

Patented July 29, 1890.

UNITED STATES PATENT OFFICE.

JOHN T. WILLIAMS, OF MOUNT VERNON, NEW YORK, ASSIGNOR TO THE INTERNATIONAL PORT-ELECTRIC COMPANY OF NEW YORK, N. Y.

ELECTRO-MAGNETIC TRANSMITTER.

SPECIFICATION forming part of Letters Patent No. 433,881, dated July 29, 1890.

Application filed October 24, 1889. Serial No. 328,088. (No model.)

To all whom it may concern:

Be it known that I, JOHN T. WILLIAMS, a citizen of the United States, residing at Mount Vernon, in the county of Westchester and 5 State of New York, have invented new and useful Improvements in Electro-Magnetic Transmitters, of which the following is a specification.

This invention relates to certain improvements in that class of electro-magnetic transmitters which I have described in Letters Patent No. 342,666, dated May 25, 1886, and No. 396,792, dated January 20, 1889; and the invention consists in the novel combinations 15 and devices hereinafter described and claimed, reference being made to the accompanying drawings, illustrating my invention, in which—

Figure 1 represents a longitudinal central 20 section in the plane $x x$, Fig. 2. Fig. 2 is a plan or top view.

Similar letters indicate corresponding parts.

In the drawings, the letters A A' A² designate a series of helices, which are wound upon 25 spools of wood or other non-conductor of electricity.

B is a track, which extends through the several helices, and is made of brass or any other suitable non-magnetic substance. The helices 30 are firmly mounted at intervals apart upon a suitable bed B', and through the flanges of the spools containing the helices A A' A², &c., extends an electric conductor C, which is insulated from the track B and from the 35 helices. This conductor connects by a wire 11 with one pole of a dynamo P or other generator of electricity, and the track B is connected by a wire 10 with the other pole of said dynamo. On each of the helices is mounted 40 a circuit-closer, consisting of a magnet D D' D², respectively, which extends in the direction of the length of the helix and the track, and can swing freely about a pivot d, arranged in a metallic base c, one of which is secured to 45 the flange of each helix. The magnet may have the form usually given to magnetic needles, but it may be made in the form of a simple rectilinear bar. In proximity to the extremity of one arm of each of the magnets 50 D D' D²—for instance, that marked n in the

drawings—is located a contact-piece e, which may consist of a spring-arm secured to the flange of the respective helix. The magnet D can be perfectly balanced, so that it normally lies in a horizontal position; but in order to insure a more prompt and quick action of the magnet, I weight the arm s of the magnet or make it of sufficient length to overbalance the arm n, so that the magnet is normally in an inclined position and the arm n 55 is out of contact with the contact-piece e. The same effect can be produced by subjecting one arm of the magnet to the action of a spring. The base c of the magnet D is connected with one end of the helix, the opposite 60 end of said helix being connected to the track B, and the contact e is connected by a wire 12 with the electric conductor C, whereby a current is established through the respective helix whenever the magnet D closes the circuit 65 at the contact e.

The carriage E, which is moved on the track B by axial magnetism or suction of the helices A A' A², is permanently magnetic, it being made of hard steel for this purpose. The opposite poles of this carriage are marked N 70 and S, respectively, and it is intended to move in the direction of arrow 1, marked thereon in Fig. 1. When the end of the carriage enters one of the helices, say helix A, its south pole S repels the south pole s of the magnet D, thereby causing said magnet to turn about its pivot and to close the circuit at the contact-piece e, so as to vitalize the helix A. The carriage is then drawn forward by the axial 75 magnetism of this helix until its center comes opposite the end s of the magnet D, when this magnet returns to its normal position. From this description it will be seen that the successive helices are not vitalized until the forward end of the carriage enters the same, and if the movement of the carriage is rapid the helices have hardly time to become vitalized, so as to produce a propelling action upon the carriage. It is therefore desirable to vitalize 80 each successive helix some time before the carriage enters the same. This object is attained by supplementary circuit-closers, which consist of magnets D⁰ D⁰', mounted on pivots f⁰ f⁰', which have their bearings in brackets 85 90 95 100

$g^0 g^0$, and the poles of which are marked $n^0 s^0$. The brackets $g^0 g^0$ are secured on blocks F F', which are of wood or other non-conductor of electricity, and firmly secured between the 5 flanges of the helices A A' A², and on these blocks are secured contact-pieces $e^0 e^0$, which connect by wires 13 with the electric conductor C, while the brackets $g^0 g^0$ connect by wires 14 with the bases c of the magnets D

10 D'. When the carriage E moves on the track B and its south pole S reaches the position indicated by a dotted line in Fig. 1, the north pole n^0 of the magnet D⁰ is attracted, and a circuit is established through the helix A some 15 time before the forward end of the carriage enters said helix. As soon as the south pole S of the carriage enters the helix A, the regular circuit-closer D also closes a circuit through this helix, and this helix is enabled to produce 20 a propelling action upon the carriage without fail.

In the example shown in the drawings the regular as well as the supplementary circuit-closers consist of magnets which are actuated 25 by the magnetic action of the carriage; but it will readily be understood that the circuit-closers could be actuated by simple contact with a non-magnetic carriage in the manner shown in my patent, No. 396,792.

30 What I claim as new, and desire to secure by Letters Patent, is—

1. The combination, with a series of helices A A' A², &c., a track B, extending through said helices, and a carriage C, of a series of regular circuit-closers D D' D² and a series 35 of supplementary circuit-closers D⁰ D⁰', all actuated by the advancing carriage and connections between the circuit-closers and the helices with a generator of electricity, substantially as described.

2. In port-electrics, the combination, with a series of helices and a track extending through the same, of a series of circuit-closers arranged between the helices and connected up in series to one coil and in multiple arc to the 45 succeeding coil, substantially as described.

3. In port-electrics, the combination, with a series of helices and a track passing through the same, of a series of regular circuit-closers and a series of supplemental circuit-closers, 50 the latter series being arranged to alternate with the first, and being connected up in series with one coil and in multiple arc with the succeeding coil, substantially as described.

In testimony whereof I have hereunto set 55 my hand in the presence of two subscribing witnesses.

JOHN T. WILLIAMS.
